An ornamental design for an erosion control blanket, as shown and described.

DESCRIPTION

FIG. 1 is a fragmentary top planar view of a new, original and ornamental design for the erosion control blanket of the invention in which dots are cross-hatched to indicate the colors blue, red, green and white;

FIG. 2 is a side view thereof;

FIG. 3 is a end view thereof;

FIG. 4 is a bottom view thereof; and,

FIG. 5 is a fragmentary top planar view of a modified version of the new original and ornamental design of the erosion control blanket of the invention in which the dots are cross-hatched to indicate the colors red, green and white, the side, end and bottom views are shown in FIGS. 2, 3 and 4, respectively.

The blankets are shown fragmented to indicate indeterminate length.
